The ornamental design for a travel cosmetic kit, as shown and described.

DESCRIPTION

FIG. 1 is a front perspective view of the travel cosmetic kit;

FIG. 2 is a top plan view thereof;

FIG. 3 is a bottom plan view thereof;

FIG. 4 is a left elevational view thereof;

FIG. 5 is a right elevational view thereof;

FIG. 6 is a front elevational view thereof;

FIG. 7 is a rear elevational view thereof; and,

FIG. 8 is disassembled view thereof.

The features illustrated by broken lines illustrate portions of the travel cosmetic kit that form no part of the claimed design.

The thin solid lines in the views have been provided for the purpose of illustrating the uniformity of the planar surfaces and the contour of the curved surfaces and are not a claimed surface pattern.
